[57] **CLAIM**

The ornamental design for a toy railway track section, as shown and described.

DESCRIPTION

FIG. 1 is a top plan view of a toy railway track section showing my new design;

FIG. 2 is a bottom plan view thereof;

FIG. 3 is a side elevational view thereof, the side opposite being substantially a mirror image;

FIG. 4 is an elevational view thereof shown on a slightly enlarged scale;

FIG. 5 is a top plan view of a modified form of the design shown in FIGS. 1 through 4;

FIG. 6 is a bottom plan view thereof;

FIG. 7 is a side elevational view thereof, the side opposite being substantially a mirror image; and

FIG. 8 is an end elevational view thereof shown on a slightly enlarged scale.

FIG. 1

FIG. 2
